UNITED STATES PATENT OFFICE.

FREDERICK R. FEITSHANS, OF LOS ANGELES, CALIFORNIA.

DESK.

1,220,405.

Specification of Letters Patent. Patented Mar. 27, 1917.

Application filed February 9, 1916. Serial No. 77,315.

To all whom it may concern:

Be it known that I, FREDERICK R. FEITSHANS, a citizen of the United States, residing at Los Angeles, in the county of Los Angeles and State of California, have invented a new and useful Improvement in Desks, of which the following is a specification.

My invention relates to desks. There are at the present time on the market two general standard forms of desk, generally designated as the "flat top desk" and the "roll top desk". The flat top desk is to all intents and purposes an ordinary table equipped with drawers, and the roll top desk is a similar table having sides projecting above the table surface, and a back provided with a rolling curtain which may be pulled outwardly and downwardly to cover the top of the desk, the curtain being locked in place to form a closed compartment over the top of the desk in which papers may be left without fear of their being molested. While the roll top desks have been in use for a long time, and are still standard in many offices, they are open to several objections, the principal objection being the fact that the back and sides extend upwardly a considerable distance above the top or working surface of the desk, and tend to shut off the light, and greatly obstruct the view of the person working at them, as well as hiding the person from the view of other people in the room. A further objection to the ordinary roll top desks with pigeon holes is the tendency of the average user to file important papers therein, these personal files being liable to become confused, and in any case being accessible to others. To overcome the objections to the roll top desk many large corporations have adopted the flat top desk, this desk not obstructing the light or shutting out the view. The flat top desk is, however, objectionable in that important papers must be gathered up whenever the user leaves the desk, or must be left in full view of any person who desires to inspect them.

The principal object of my invention is to provide a desk which will have practically all the advantages of a flat top desk, as to the practical absence of objectionable structure above the working surface, and which at the same time will be provided with a rolling curtain which may be pulled over and locked to hide papers lying on top of the

desk, should the user desire to do so. Letter trays and papers take up comparatively little vertical height, and it is possible in my invention to utilize a rolling curtain which incloses a space having a small vertical height, such a small height being amply sufficient for containing any papers, letter trays, or the like.

It is very common practice to have on desks, telephones, lights, ink stands, or the like, which are much too high to go in such a small vertical space, and it is a further object of my invention to provide a free portion of the desk top, at the back thereof, which is not covered by the curtain, this free portion being utilized to contain lights, telephones, check protectors, dating stamps, or other appliances, which would be too high to go inside the desk and which at the same time are absolutely essential to the daily work of the user of the desk.

Further objects and advantages will be made evident hereinafter.

In the drawings, which are for illustrative purposes only:

Figure 1 is a perspective view of a desk equipped with my invention.

Fig. 2 is a vertical section through the center of the desk, showing the method of securing and rolling up the curtain.

Fig. 3 is an alternate form of my invention.

Fig. 4 is a small detail, showing the method of securing the curtain in the sides.

Fig. 5 is a sectional view of the spring roller.

In the form illustrated in the drawings, the top or working surface 11 of the desk is supported on legs 12, the space below the top being filled with drawers 13 in any suitable arrangement, that shown being more or less standard. End panels 14 and 15 are provided, these end panels having projections 16 which extend a short distance above the top of the desk at either end thereof. Grooves 17 are cut on the inner side of the projections 16, these grooves consisting of a central straight portion 18 and curved portions 19 and 20. In the form of the invention shown in Fig. 2, a box 21 is located inside the desk below the top extending completely across the back thereof. A spring roller 22 is placed in the box 21. One construction of this roller is shown in Fig. 5, in which 23 and 24 are bearings secured on the ends 25 and

26 of the box 21, and 27 is a curtain roller to which one end of a curtain 28 is secured. A trunnion 29 is secured in one end of the roller 27, turning freely in the bearing 23. 5 A round rod 30 is rigidly secured in the bearing 24, extending into a cylindrical cavity 31 formed in the roller 27 which is provided with an end bearing 32 which turns freely on the rod 30. A spiral spring 10 33 is wound around the rod 30 inside the cavity 31, one end thereof being secured by being passed through the rod 30 at the point 34, the other end thereof being secured to the bearing 32 at the point 35. 15 The direction of winding of the spring 33 is such that it tends to roll the curtain 28 up in the manner shown in Fig. 2. One end of the curtain 28 being secured to the roller 27, the other end is secured to a cross 20 bar 40, this cross bar extending completely across the desk inside the projections 16 and fitting into a cavity formed in the top 11 of the desk when the desk is as shown in Fig. 2. The curtain 28 is formed of 25 canvas or other flexible member 41 and a series of metal or wooden slats 42, the ends of the slats 42 projecting into the grooves 17 at either end in the same manner as the similar members in an ordinary roll 30 top desk. A lock 45 is provided for securing the cross bar 40 to the front edge 46 of the desk when the curtain is drawn forward into the position shown in Fig. 1.

It will be noted that a free space 47 is 35 left at the back of the desk outside the curtain when the curtain is pulled into the closed position. This free space is used for holding a telephone, as shown at 48, or a desk lamp, as shown at 49. The desk lamp 40 and telephone may, of course, have any height, or any of the other common office 50 appliances may be left standing on this free space. The free space is very important in the actual operation of the desk, as practically every office worker has tools or appliances which would not go into the small space provided below the curtain 28 when the desk is closed.

In the form of my invention illustrated 55 in Fig. 3, a curtain 50 is shown, this curtain being secured at 51 to the underside of the top of the desk 52 and being provided with a cross bar 53 which forms a ledge on the top of the desk, no cavity being provided for it to fit into. This arrangement of the curtain is somewhat cheaper to install than the arrangement shown in 60 Fig. 2, but it can only be used where the desk has a closed back which is in itself objectionable to many purchasers. The arrangement of the cross bar, shown at 53, in Fig. 3, may be used with the type of curtain shown in Fig. 2, if desired. The slight projection of the cross bar above the 65 flush surface of the top of the desk is pre-

fered by some users as it prevents papers being pushed onto the free space 47, serving as a stop for such papers so that the desk can be instantly closed without the necessity for moving them.

It will be seen that the desk illustrated and described has certain peculiar advantages. It is very ornamental in appearance, does not obstruct the light when either 70 opened or closed, and has in fact all the advantages of a flat top desk, plus many of the advantages of the old and now largely obsolete roll top desk.

By the use of the arrangement shown in Fig. 2, an open back desk can be provided, 80 or by using the arrangement shown in Fig. 3, a closed back desk can be provided. In either case, the cross bar 53 can be used, forming a ledge to limit the backward movement of papers or other objects on top of 85 the desk, and in either case the free space 47 may be left for carrying telephones, or other high objects. By the use of my invention all the advantages of both types of desks are obtained, my type of desk promoting to a very great degree that high personal efficiency which is now one of the objects of all organizations.

I claim as my invention:—

1. In a desk; a flat top having a slot at 95 one side thereof, said slot being at least sufficiently far from the back of said top to allow a desk telephone or other device of similar proportions to rest thereon; a projection at either end of said top, said projections extending up from said top a distance somewhat less than the height of an ordinary telephone, extending along the whole length of either edge, and being provided with grooves on the inner sides thereof, said grooves registering at one end with said slot and extending down at their forward end to a point near said top; and a curtain sliding in said slot and said grooves.

2. In a desk; a flat top having a slot at 110 one side thereof, said slot being at least sufficiently far from the back of said top to allow a desk telephone or other device of similar proportions to rest thereon; a projection at either end of said top, said projections extending up from said top a distance somewhat less than the height of an ordinary telephone, extending along the whole length of either edge, and being provided with grooves on the inner sides thereof, said grooves registering at one end with said slot and extending down at their forward end to a point near said top; and a flexible curtain extending through said slot to a point below said top, said curtain sliding in and being guided by said grooves.

3. In a desk; a flat top having a slot at one side thereof, said slot being at least sufficiently far from the back of said top to allow a desk telephone or other device of simi- 130

lar proportions to rest thereon; a projection at either end of said top, said projections extending up from said top a distance somewhat less than the height of an ordinary telephone, extending along the whole length of either edge, and being provided with grooves on the inner sides thereof, said grooves registering at one end with said slot and extending down at their forward

10 end to a point near said top; a curtain slid-

ing in said slot and said grooves; and a cross bar secured to the forward end of said curtain and so shaped as to drop into and close said slot when said curtain is slid back through said slot.

15

In testimony whereof, I have hereunto set my hand at Los Angeles, California, this 1st day of February, 1916.

FREDERICK R. FEITSHANS.
